COLLISION BUMPER DEVICE.

Application filed August 28, 1926. Serial No. 132,092.

This invention relates to novel constructions of derailing collision bumper devices with which railroad locomotives and rolling stock may be equipped; and the invention 5 has reference, more particularly, to cooperative bumper devices adapted to be respectively mounted on the front ends of railway locomotives and on the rear end cars of railway trains, for the purpose of deflecting and derailing locomotives which may meet in rear end collision with preceding trains.

In the operation of railroad trains, accidents of the rear end collision type are of more or less frequent occurrence, notwithstanding the exercise of the most careful train dispatching methods and control. Such accidents usually entail considerable loss of life when occurring in passenger service, as well as great property loss when 20 occurring in freight service. The principal factor accounting for such losses of life and property arising out of accidents of said rear end collision type lies in the fact that such collisions in the majority of cases involve the telescoping of the cars of the train collided with by the colliding locomotive, and this notwithstanding the general use of steel cars in the passenger service. The telescoping effects of such collisions 30 also quite frequently result in deaths by scalding due to escape of steam from the colliding locomotive in both passenger and freight accidents, as well as in destructive fires in freight accidents by which large amounts of freight are destroyed by burning in addition to such as may be destroyed by the direct effects of the collision.

It is the object of the present invention to provide means, effective upon the occurrence of such collisions, whereby losses of both life and property may be greatly minimized, if not altogether prevented. To this end our invention consists in providing cooperative collision bumper devices, the members of which are respectively mounted and fixed, one on the front end of the locomotive, or electric engine as the case may be, and one on the tail end of rear cars, cabooses or other types of rolling stock; said 45 bumper devices being operative on mutual engagement and contact at the moment of collision to lift and derail the colliding locomotive and thereupon shunt, turn or deflect the same from and out of line with the cars 50 of the preceding train with which it col-

lides, so as to positively prevent any telescoping invasion by said colliding locomotive of the cars of said preceding train.

Other objects of this invention, not at this time more particularly enumerated, will 60 be clearly understood from the following detailed description of the same:

With the objects of our present invention in view, the same consists, primarily, in the novel construction and arrangement of cooperative derailing collision bumpers hereinafter set forth; and, furthermore, the invention consists in the novel arrangements and combinations of the various devices and parts, as well as in the details of the 65 construction thereof, all of which will be hereinafter more fully described in the following specification, and then finally embodied in the claims which are appended thereto. 75

The invention is clearly illustrated in the accompanying drawings, in which:—

Fig. 1 is a perspective view of the front end of a locomotive and the rear end of a preceding train shown respectively equipped with the respective cooperative collision bumper devices made according to and embodying the principles of our present invention. 80

Fig. 2 is a diagrammatic plan view of said cooperative collision bumper devices as normally related respectively to the front end of an approaching locomotive and the rear end of a preceding train in the path thereof; Fig. 3 is a similar view showing 90 said bumper devices at the moment of colliding contact; Fig. 4 is a similar view showing the shunting or deflecting movement of the locomotive bumper device relative to the rear end bumper device of said preceding train; and Fig. 5 shows the completion of the shunting or deflecting operation. 95

Fig. 6 is a perspective view of the locomotive bumper device; and Fig. 7 is a perspective view of the rear end bumper device for the rear car of a preceding train. 100

Fig. 8 is a diagrammatic vertical cross section, taken on line 8—8 in Fig. 3; and Fig. 9 is a similar view, taken on line 9—9 in Fig. 4. 105

Figs. 10 and 11 are respectively diagrammatic plan views of the respective cooperative collision bumper devices, modified to include ear coupling means, and having 110

movable sections to expose said car coupling means for use; said movable sections being shown closed in these views, so that the bumper devices are operative in the event of collision; Fig. 12 is a similar view of one bumper device showing the movable section opened to expose the car coupling means for use; Fig. 13 is a diagrammatic plan view showing the bumper devices as arranged for car coupling operation; Fig. 14 is a fragmentary perspective view of the locomotive bumper device opened to expose its car coupling member; and Fig. 15 is a similar fragmentary perspective view of the same in closed condition.

Similar characters of reference are employed in all of the hereinabove described views, to indicate corresponding parts.

Referring now to said drawings, the reference character 1 indicates a railway locomotive, and 2 the rails of the track upon which the same moves. The reference character 3 indicates a rear car of a train ahead of the locomotive on the same track, such, for example, as a rear end observation car of a preceding passenger train.

Rigidly mounted and secured in connection with the body or frame of said locomotive 1, at the front end thereof, and at a level substantially corresponding to the level of the body frames of the railway cars or similar rolling stock, is a bumper head 4 extending transversely across said front end of the locomotive so as to project forwardly therefrom. The forward or free end of said bumper head 4 is formed to provide an oblique sheer face 5 extending from the inner side of the locomotive forwardly and outwardly at a desired predetermined angle, which is preferably about forty-five degrees relative to the central longitudinal axis of the locomotive. Said sheer face 5 is of a length adapted to extend the same substantially outwardly beyond the central longitudinal axis of said locomotive. Coincident with the upper peripheral edge of said sheer face 5, and preferably integrally formed with said bumper head 4, is an over shot shoulder or lip 6, the under surface of which is shaped to form a descending inclined plane 7 extending rearwardly and downwardly from the outer lateral extremity or end of said shoulder or lip 6 to the inner lateral extremity or end thereof, said inclined plane 7 thus providing an elevator plane for purposes subsequently to be described.

Rigidly mounted and secured in connection with the body frame of a railway car, such, for example, as an observation car, pullman sleeper, passenger coach, freight car, caboose, or any other desired type of railway rolling stock, is a rear end bumper member 8 extending transversely across the tail end of such railway car so as to project rearwardly therefrom. The rear or free end

of said bumper member 8 is formed to provide an oblique sheer face 9 extending from the outer side of the car rearwardly and inwardly at a desired predetermined angle, which is preferably about forty-five degrees relative to the central longitudinal axis of said car. Said sheer face 9 is of a length adapted to extend the same substantially inwardly beyond the central longitudinal axis of said car. Coincident with the lower peripheral edge of said sheer face 9, and preferably integrally formed with said bumper member 8, is an under shot shoulder or lip 10, the upper surface of which is shaped to form an ascending inclined plane 11 extending forwardly and upwardly from the inner lateral extremity or end of said shoulder or lip 10 to the outer lateral extremity or end thereof, said inclined plane 11 thus providing a lifting plane for purposes subsequently to be described.

The respective bumper head 4 and bumper member 8 are made of substantial thickness or height, and are so connected respectively with the locomotive and with the railway car as to occupy corresponding levels relative to the road-bed or track 2, whereby in operation the same are opposed one to the other for mutual cooperation. It will also be understood that any desired character and method of construction may be employed to rigidly and strongly build said bumper devices respectively into the locomotive and railway car structures so as to operatively incorporate the same therewith.

In making use of said bumper devices in practice, each locomotive in regular service will be equipped with a bumper head 4, and in making up either passenger or freight trains, the rear car of each such train will be equipped at its tail end with a bumper member 8.

In operation, if in the movement of trains equipped with our above described cooperative collision bumper devices, the locomotive of a following train should collide with a preceding train, the bumper head 4 of such locomotive would be brought into engagement with the bumper member 8 of the rear car of such preceding train. Inasmuch as the sheer faces of said respective bumper devices extend respectively in opposite directions beyond the central longitudinal axes of the respective trains, the respective sheer faces 5 and 9 will overlap each other at the moment of contact (see Fig. 3). Since, however, the sheer face 5 of the bumper head 4 extends from the inner side outwardly beyond the central longitudinal axes of the trains, and the sheer face 9 of the bumper member 8 extends from a point inwardly of the central longitudinal axes of the trains outwardly toward the outer side thereof, continued forward movement of the colliding locomotive relative to the rear end of the

preceding train will cause the sheer face 5 of the former to ride outwardly on the sheer face 9 of the latter, thus tending to laterally deflect the forward movement of said locomotive outwardly and away from said rear end of said preceding train (see Figs. 4 and 5). In addition to this sheering or deflecting movement, and in aid thereof, the elevator plane of the locomotive bumper head 4 will tend to ride upwardly on the lifting plane 11 of the rear end bumper 8. The effect of the cooperative action of said elevator and lifting planes is two-fold; first, it tends, by imposing the weight of the locomotive on the rear end bumper member 8, to hold the rear car of the preceding train down upon the rails 2, and, secondly, by lifting the fore end of the locomotive, it causes the flanges of the wheels of its pilot truck 20 to be lifted clear of the rails so as to offer no impedance to the lateral deflecting or sheering aside of the locomotive, whereby the same is both derailed and turned aside from the path of said preceding train (see Figs. 8 and 9). It will be understood, that the force of the collision in itself will be sufficient to cause the cooperative movement of the locomotive bumper head 4 relative to the rear end bumper member 8, whereby both 25 the derailing and the shunting or deflecting of the colliding locomotive is induced.

As will be evident, the derailing and shunting or deflecting of the locomotive will prevent the latter from plowing directly into the preceding train with the telescoping action so commonly accompanying accidents of the rear end collision type, and consequently the highly destructive effects both upon life and property which are attendant on such 30 telescoping action is positively prevented. It is calculated that loss of life and property consequent upon rear end collision accidents, may, in all probability, be reduced to the extent of seventy-five per cent or more by the 35 use of anti-telescoping collision bumpers such as our above-described invention provides. By thus eliminating losses of life and property, the use of our invention will therefore tend to greatly lessen financial losses 40 in railway operation by reducing the amount of damage claims arising out of rear end collision and similar accidents.

In the illustration of the above-described bumper devices, the bumper head 4 is obliquely and rearwardly cut away on its outer side, as at 12; and the bumper member 8 is obliquely and forwardly cut away on its inner side, as at 13. Such arrangement, while not absolutely essential, is preferable since 45 it reduces the extent of projection of the respective devices within desired minimum limits, besides effecting a saving in weight and bulk, and thus economizing the cost of production.

60 Referring now to Figs. 10 to 15 of the

accompanying drawings, we have shown a form of our novel anti-telescoping collision bumpers, modified to include any standard type of car coupling devices. In such modified form, the bumper head 4 is provided with a movable section 4' at its free extremity, which is preferably connected to the main body portion by a suitable hinge connection 14. Said movable section 4' is provided with a suitable keeper flange 15 movable into a corresponding seat 16 of the main body portion, when the movable section is in closed relation to the latter; in like manner, the portion of the shoulder or lip 6 springing from the movable section 4' is 70 provided with a tongue member 17 adapted to interlock with a socket or recess 18 formed in the main body portion when the movable section is in closed relation to the latter. Said keeper flange 15 and tongue member 17 75 tend to firmly hold said movable section 4' against displacement, when in closed relation to said main body portion, under which condition the movable section normally 80 functions as an operative part of the collision bumper.

In order to lock said movable section 4' in closed relation to said main body portion, the keeper flange 15 of the former is provided with one or more openings 19 corresponding 95 with one or more openings 20 provided in the underlying part of said main body portion, and mutually adapted to receive detachable lock-pins 21, which are preferably connected against loss by flexible connections 100 22 anchored to said main body portion 4.

Secured to said main body portion 4, to project from the end face thereof which is exposed by the movement of said movable section to open position (see Fig. 12), is any 105 suitable form of car coupling device 23. The rear or meeting face of said movable section 4' is provided with a cavity 24 to receive the projecting coupling device when said movable section 4' is in normal closed 110 position.

As shown in Fig. 11, the rear end bumper member 8 may be provided with a similarly constructed hinged movable section 8', which may be similarly opened to expose for use a 115 suitable car coupling device 25 secured to and projecting from the end face thereof, as shown in Fig. 13 also.

In Fig. 13 illustration is made of the manner in which, upon the opening of their respective movable sections 4' and 8', the coupling devices 23 and 25 of the respective modified bumper head 4 and bumper member 8 may be mutually interengaged to couple a locomotive and car respectively equipped therewith. It will also be understood, that the locomotive bumper head 4, modified as above described, makes it possible to couple the same with any car having corresponding coupling means, whether equipped 120 125 130

with the rear end bumper member 8 or not.

From an inspection of Figs. 10 and 11 together, in which the above described modified bumper head and bumper member are shown with their movable sections 4' and 8' closed, it will be apparent, that when so arranged the said bumpers will cooperate in event of collision, in the same manner and with all of the advantages already hitherto above described.

In the accompanying drawings we have shown and in the above specification have described our invention in preferred forms and by way of example, but obviously many alterations and variations may be made therein which will still be comprised within its spirit. Generally speaking, therefore, we desire it understood that we do not limit ourselves to any specific form or embodiment of our present invention, except in so far as may be required by the scope of the following claims.

Having thus described our invention, we claim:

1. Cooperative collision bumper devices, respectively for connection with the forward end of locomotives and the rear end cars of railway trains, comprising a locomotive bumper having at its free end a transversely oblique sheer face inclining forwardly and outwardly from its inner side, a rear car bumper having at its free end a transversely oblique sheer face inclining rearwardly and inwardly from its outer side, an under shot shoulder bordering the lower margin of said latter sheer face, the upper surface of said shoulder being formed to provide an outwardly ascending inclined plane, and said locomotive bumper having means to engage and ride upwardly on said inclined plane when the sheer faces of said respective bumpers operatively engage.

2. Cooperative collision bumpers, respectively for connection with the forward end of locomotives and the rear end cars of railway trains, comprising a locomotive bumper having at its free end a transversely oblique sheer face inclining forwardly and outwardly from its inner side, a rear car bumper having at its free end a transversely oblique sheer face inclining rearwardly and inwardly from its outer side, an under shot shoulder bordering the lower margin of said latter sheer face, the upper surface of said shoulder being formed to provide an outwardly ascending inclined plane, and said locomotive bumper having an over shot shoulder bordering the upper margin of its sheer face, the under surface of said latter shoulder being formed to provide a reverse inclined plane cooperative with the ascending inclined plane of said rear car bumper.

3. Cooperative collision bumper devices, respectively for connection with the forward end of locomotives and the rear end

cars of railway trains, comprising a locomotive bumper having at its free end a transversely oblique sheer face inclining forwardly and outwardly from the inner side of the locomotive to a point appreciably beyond its central longitudinal axis, a rear car bumper having at its free end a transversely oblique sheer face of corresponding angle inclining from a point inwardly spaced from the central longitudinal axis of the car forwardly and outwardly toward the outer side of the latter, said rear car bumper having a rearwardly projecting shoulder bordering the lower margin of its sheer face and shaped on its upper side to provide an inclined plane ascending from the inner end of said sheer face toward the outer end thereof, and means bordering the upper margin of said locomotive bumper sheer face to cooperate with said inclined plane.

4. Cooperative collision bumper devices, respectively for connection with the forward end of locomotives and the rear end cars of railway trains, comprising a locomotive bumper having at its free end a transversely oblique sheer face inclining forwardly and outwardly from the inner side of the locomotive to a point appreciably beyond its central longitudinal axis, a rear car bumper having at its free end a transversely oblique sheer face of corresponding angle inclining from a point inwardly spaced from the central longitudinal axis of the car forwardly and outwardly toward the outer side of the latter, said rear car bumper having a rearwardly projecting shoulder bordering the lower margin of its sheer face and shaped on its upper side to provide an inclined plane ascending from the inner end of said sheer face toward the outer end thereof, and said locomotive bumper having a forwardly projecting shoulder bordering the upper margin of its sheer face and shaped on its under side to provide an inclined plane descending from the outer end of said sheer face toward the inner end thereof, all for the purposes described.

5. An anti-telescoping collision bumper for connection with the forward ends of railway locomotives, comprising a forwardly projecting bumper head, said bumper head having at its free end a transversely oblique sheer face inclining forwardly and outwardly from the inner side of the locomotive toward the outer side thereof, and said bumper head having a forwardly projecting shoulder bordering the upper margin of its sheer face and shaped on its under side to provide an inclined plane descending from the outer end of said sheer face toward the inner end thereof.

6. An anti-telescoping collision bumper for connection with the tail ends of railway cars, comprising a rearwardly projecting bumper member, said bumper member

having at its free end a transversely oblique sheer face inclining forwardly and outwardly from the inner side of the car toward the outer side thereof, and said bumper member having a rearwardly projecting shoulder bordering the lower margin of its sheer face and shaped on its upper side to provide an inclined plane ascending from the inner end of said sheer face toward the outer end thereof.

7. An anti-telescoping collision bumper for connection with the forward ends of railway locomotives, comprising a forwardly projecting bumper head, said bumper head having at its free end a transversely oblique sheer face inclining forwardly and outwardly from the inner side of the locomotive toward the outer side thereof, the outer extremity of said bumper being formed to provide a movable section, means to hinge said movable section to the main body of said bumper, means to secure said movable section in normal closed position relative to said main body, and a car coupling means connected with said main body so as to be concealed when said movable section is closed but exposed for use when the latter is opened.

8. An anti-telescoping collision bumper as set forth in claim 5, in which the outer extremity of the bumper is formed to provide a movable section, means to hinge said movable section to the main body of said bumper, means to secure said movable section in normal closed position relative to said main body, and a car coupling means connected with said main body so as to be concealed when said movable section is

closed but exposed for use when the latter is opened.

9. An anti-telescoping collision bumper for connection with the tail ends of railway cars, comprising a rearwardly projecting bumper member, said bumper member having at its free end a transversely oblique sheer face inclining forwardly and outwardly from the inner side of the car toward the outer side thereof, the outer extremity of said bumper being formed to provide a movable section, means to hinge said movable section to the main body of said bumper, means to secure said movable section in normal closed position relative to said main body, and a car coupling means connected with said main body so as to be concealed when said movable section is closed but exposed for use when the latter is opened.

10. An anti-telescoping collision bumper as set forth in claim 6, in which the outer extremity of the bumper is formed to provide a movable section, means to hinge said movable section to the main body of said bumper, means to secure said movable section in normal closed position relative to said main body, and a car coupling means connected with said main body so as to be concealed when said movable section is closed but exposed for use when the latter is opened.

In testimony, that we claim the invention set forth above we have hereunto set our hands this 27th day of August 1926.

WILLIAM H. RADEMAEKERS, SR.
WILLIAM H. RADEMAEKERS, JR.
